SKIVING MACHINE

Milton H. Roske, Malden, Mass., assignor to
 United Shoe Machinery Corporation, Fleming-
 ton, N. J., a corporation of New Jersey

Application September 8, 1949, Serial No. 114,635

13 Claims. (Cl. 69—9.5)

1

This invention relates to skiving machines, and more particularly to a skiving machine for preparing the edge of a shoe upper part, or other work piece, for a folding operation as performed by the improved folding machine disclosed in United States Letters Patent No. 2,526,691, granted October 24, 1950, upon my application, the fold produced by this machine being characterized by its narrowness.

It has been a common practice in high quality shoemaking to finish certain exposed edges of upper parts by folding the margin of the material upon itself so that these edges are covered by the grain side of the material, and therefore have the same appearance as the rest of the exposed surfaces of the upper parts. Excessive thickness of the finished edge is avoided by skiving the margin of the work to a thin feather edge. Hence, after the fold has been made, the thickness of the folded portion is no greater than that of the rest of the work.

Heretofore, it has been considered necessary that the skived margin of the work be wide enough to overlap the unskived flesh side of the work, that is, of a width which is a multiple of the thickness of the stock. It is evident that this practice results in appreciable waste, since a considerable area of stock is given over to the folding allowance. Moreover, when the skiving cut is made on a gradual taper, as is commonly the case, the flexibility of the thinly skived margin tends to make the gaging of the work erratic during the folding operation, and to the extent that the width of the fold varies, the final shape of the work departs from that desired.

In view of the foregoing, an object of the invention is to provide an improved skiving machine for producing a skiving cut so extremely narrow that the width of the feather to be folded around the edge of the work is approximately equal to the thickness of the stock. By this expedient the folding allowance is reduced to a negligible amount with a corresponding saving in material cost. A further object is to obtain, in a skived edge of this narrowness, an abrupt shoulder which will facilitate the gaging of the work during the folding operation and establish a fold-line parallel to the edge of the work, thereby insuring a true contour in the folded edge.

This form of skived edge is produced by the illustrated machine because of the provision therein of novel work forming and feeding means constructed and arranged to impart an abrupt and well defined bend in the work close to its

2

edge, and to present the work to a skiving knife in such a manner that the bent margin is skived to a thin feather from the vertex of the bend outwardly to the edge. Because of the sharpness of the bend in the work when the skiving cut is made, the portion of the cut extending from the vertex of the bend across the flesh side of the work forms an abrupt shoulder, when the feather is straightened, around which the feather is ultimately folded by the use of my improved machine mentioned above, without overlapping the unskived flesh side of the work.

The above mentioned work forming means comprises a feed roll which is distinguished from feed rolls of usual form by a narrow rim at one end of the roll, the width of the rim being approximately equal to the thickness of the stock to be skived. Contiguous to this rim is a flaring portion, the surfaces of the rim and the flaring portion being disposed at an angle to each other and forming a definite ridge at their junction over which the work is abruptly bent. Invention is to be recognized in the combination, with such a feed roll, of a presser foot constructed and arranged to hold the work closely against the feed roll at and at each side of the above mentioned ridge.

In order that the feed roll and presser foot shall have as effective a holding action upon the work as possible, inwardly from the margin to be bent, the width of the flared portion of the feed roll and the corresponding portion of the presser foot is considerably greater than the width of the rim. It is therefore certain that all portions of the work in which the bend and skiving cut occur will be held closely against the roll, and that the abruptness of the bend necessary for producing the above-mentioned shoulder at the edge of the work will be obtained.

Contributing with the above-mentioned work forming means to the formation of the shoulder, as well as to the extreme narrowness of the skiving cut, is the fact that the illustrative knife is tubular and of small diameter. It is evident that the curved cut made by such a knife spans a narrower margin of the work and extends more directly through it than does the cut made by a disk knife or one of any other form.

Another object of the invention is to obviate, as much as possible, any tendency of the work to become jammed in the machine during the skiving operation. To this end, the invention provides an improved yielding drive for the usual feed disk which cooperates with the feed roll to feed the work, and also an edge gage so disposed

with respect to the presser foot and feed roll that the clearance space between these latter members and the gage extends crosswise of the work and the direction of pressure exerted by the work on the gage.

Other novel structure which provides for the disposal of the skiving chips made by the illustrated knife forms the subject-matter of, and is claimed in, another application Serial No. 305,217, filed on August 19, 1952, as a division of this application.

These and other features of the invention will now be described in greater detail and will be defined in the appended claims.

In the drawings,

Fig. 1 is a front elevation of an illustrative machine embodying the invention;

Fig. 2 is a side elevation of the machine as viewed from the left;

Fig. 3 is a plan view;

Fig. 4 is a front elevation illustrating, at an enlarged scale, the operating instrumentalities of the machine and the relation of a work piece to them during a skiving operation;

Fig. 5 is a magnified front elevation of portions of the operating instrumentalities adjacent to the point of operation of the knife on the work;

Fig. 6 is a magnified and diagrammatical view illustrating a portion of the feed roll in front elevation and the form of the skiving cut made upon the work;

Fig. 7 is a sectional elevation of the knife and its mounting, the section being taken vertically through the axis of the knife; and

Fig. 8 is a perspective view of portions of the feed roll, presser foot and edge gage.

The illustrated machine comprises a rotary feed roll 10 (Figs. 1 and 4) having a novel form, as will be more fully pointed out later, and comprising a hub 12 at one end, a narrow rim 14 at the other end, the rim and hub being connected by an intermediate flared portion 16. A work piece W to be skived is positioned with its edge flush with the outer end of the rim 14 by an edge gage 18, upon which is pivotally mounted at 20 a presser foot 22 which holds the work against the feed roll throughout the width of the rim 14 and flared portion 16, as illustrated in Fig. 5, to form an abrupt bend in the work very close to its edge.

Immediately behind the presser foot is the cutting edge of a tubular knife 24 which is sharpened with an outside bevel (Fig. 7). A feed disk 26 holds the work W, adjacent to the presser foot, against the hub 12 of the feed roll, and cooperates with the latter to advance the work toward the knife.

With the machine in proper adjustment, it produces a skiving cut, as illustrated in Fig. 6, by which most of the material is removed from a narrow margin of the work at the flesh side leaving a very thin feather 28, the length of which is about equal to or even less than the thickness of the stock. This feather is bent out of the plane of the rest of the work when the skiving cut is made. When the work piece is removed from the machine the feather straightens out (into its broken line position Fig. 6), and then projects from an abrupt shoulder 30 which results from the angular relation between the knife and the flared portion 16 of the feed roll.

This skiving cut is characterized by its extreme shortness, reduces the skiving and folding allowances to a minimum, and prepares the work most

advantageously for the formation of the narrow fold at the edge of the work which is produced by my improved folding machine referred to above.

The knife 24 is threaded into a sleeve 32 (Figs. 2 and 7) and is positioned in coaxial relation therewith by the engagement of a tapered shoulder 34 on the knife with a complementary socket formed in the sleeve. The sleeve is mounted to rotate freely upon ball bearings 36 which are carried by a housing 38, the latter being fixed in position and being rigidly attached to a standard 40 which extends upwardly from the base 42 of the machine. The knife is driven by a belt 44 which runs over a pulley 46, the latter being threaded on the rear end of the sleeve 32 and being arranged to hold the inner races of the ball bearings 36 in assembled relation upon the sleeve.

The belt 44 is driven by a pulley 48 (Figs. 1 and 3) which is fixed to the input shaft 50 of a reduction gear unit 52 to which power may be supplied by any suitable means such as a belt arranged to run upon a pulley 54 fixed to the shaft 50. The unit 52 has an output shaft 56 on the inner end of which is fixed a pulley 58. This pulley drives a belt 60 which runs over another pulley 62 carried by a shaft 64, the above-mentioned feed roll being fixed to the other end of the shaft. This shaft is rotatably mounted in bearings 66, 68 (Fig. 1) which project downwardly from a frame 70 upon which all the work engaging members, except the knife, are mounted. As will be described below, provision is made for adjusting the position of the frame in various ways so that any desired relation of the work to the knife may be obtained without upsetting the adjustment of the other work engaging members relatively to each other.

The feed disk 26 is fixed to the lower end of a stem 72 which is mounted to rotate and slide axially within bearings 74 formed in a bracket 76 which is adjustable axially of the feed roll 10 in order that the feed disk may be positioned properly with regard to the hub 12. For this purpose, a slide 78 on the bracket 76 is arranged to fit within a recess formed in the back of the frame 70 and is held in adjusted position by a screw 80 which extends through an elongated slot 82 in the frame and is threaded into the slide.

The feed disk 26 is driven from the shaft 64 by connections comprising gearing 84 which operates a shaft 86 mounted to rotate in a vertical position at the right hand side of the frame 70. Gearing 88 connects the shaft 86 with another shaft 90 which is mounted to rotate freely in a horizontal position in the upper part of the frame 70. A shaft 92, mounted to rotate in a bearing 94 on the bracket 76, is aligned with the shaft 90 and is connected thereto by a friction clutch comprising a socket 96, fixed to the shaft 92, and a complementary driving element 98 which is splined to the shaft 90. The driving force which this friction clutch is capable of transmitting can be adjusted by changing the position of a collar 100 along the shaft 90, thereby to vary the compression in a spring 102 disposed between the collar and the driving element 98, and arranged to hold the latter element against the socket 96. A beveled pinion 104 fixed to the shaft 92 meshes with a similar pinion 106 having a hub which fits within the bearing 74, the lower end of the hub having fixed thereto a collar 108. A spring 110, coiled around the stem 72 and fixed to the collar 108, is also fixed to another collar 112 which may be secured in any desired position of adjustment

axially of the stem 72, in order to vary the compression of the spring 110.

This adjustment of the collar 112 is employed to vary the pressure with which the feed disk 26 holds the work against the feed roll 10, and hence the feeding force provided by these members. It will further be evident that the feed disk is resiliently driven in rotation through the spring 110, and that the above-mentioned frictional clutch will slip in response to any resistance to turning of the feed disk in excess of that for which the spring 182 and collar 100 are adjusted. Thus, any tendency of the work to become jammed between the feed roll, and the presser foot 22 or the edge gage 18, on account of the feeding action is avoided.

The above-mentioned adjustments of the frame 70 by which the skiving cut may be varied will now be described in detail. In order to vary the taper of the feather 28, the frame 70 (and hence the feed roll 10) is mounted for angular adjustment about the high point of the rim 14 at its inner edge. For this purpose the rear side of the frame has an arcuate groove 114 within which fits a similarly shaped rib 116 projecting from a slide 118. The frame is secured to the slide by a pair of screws 120 which pass through arcuate slots in the frame and are threaded into the slide.

In order to adjust the feed roll vertically toward and away from the knife, and therefore to control the thickness of the feather 28, the slide 118 is mounted in a dove-tailed slideway formed in the upright portion 122 of an angular bracket having a base 124. An adjusting screw 126, threaded in the slide 118 and bearing at its lower end against the base 124, can be turned to adjust the slide 118 vertically.

Adjustment of the feed roll 10 horizontally toward and away from the knife is effected by moving the base 124 along a slideway 128 formed in the base 42, this latter adjustment being under the control of a knob 130 which is fixed to a screw 132 arranged to rotate without axial movement in the base 42, and threaded into a nut which is carried by the base 124. The base 124 may be fixed in any desired position of adjustment by a clamp screw 134 which passes through an elongated slot 136 in the base 124 and is threaded into the base 42. Any desired combination of the above-mentioned horizontal and vertical adjustments for the feed roll 10 may be employed to secure the required taper and thickness of the feather 28, as well as the necessary clearance between the knife and the work.

Although all the above adjustments are small in the ordinary use of the machine, and are not likely to disturb the driving relation between the belt 60 and the pulleys 62 and 58, proper tension of the belt can be maintained by adjusting vertically an idler pulley 138 (Fig. 3) which is carried by a bracket 140 adapted to be secured in various positions of adjustment upon the upright 122 by a screw 142.

Various structural features of the illustrated feed roll 10, presser foot 22 and edge gage 18 contribute materially to the capacity of the machine to produce the extremely short and thin feather 28, as well as to form the abrupt shoulder 30, near the edge of the work, which is to be covered by the feather during the subsequent folding operation. These features of the machine will now be described in detail with reference to Figs. 4 and 5.

The rim 14 of the feed roll is extremely narrow,

its width being approximately equal to, but no greater than the thickness of the work to be skived. The flared portion 16 is contiguous to the rim, is frusto-conical in the illustrated machine, and of appreciable width, i. e. a multiple of the width of the rim. The diameter of the flared portion gradually diminishes toward the hub 12 which is contiguous to the smaller base of the portion 16.

10 In order that the work may be bent abruptly over the ridge at the junction of the portion 16 and the rim 14 it is essential that the work be held securely against the feed roll at, and at each side of, the above-mentioned ridge. This result is achieved in the illustrated machine by the presser foot 22 which has a work-engaging surface substantially complementary to the sectional form of the portion 16 and rim 14 of the feed roll. That is, its surface has the form of an inverted V, one of its angular sides 22a being adapted to hold a narrow margin of work against the rim 14, and its other side 22b being arranged to hold the work, inwardly from the aforesaid narrow margin, against the flared portion 16 throughout the width of it.

20 It will be observed with reference to Fig. 6 that the skiving cut extends through the flesh side of the work considerably inside of a point opposite to the base of the feather 28. It is therefore desirable that a width of material, considerably greater than the width of the rim 14 be held straight and in engagement with the flared portion 16 when the skiving cut is made. For this reason the width of the flared portion 16, 30 and also the width of the side 22b of the presser foot has been made several times greater than the width of the rim 14. Such extensive bearing of the presser foot and roll upon the body of the work also insures that a sharp or abrupt angular bend will be formed in the work at the point where the skiving cut is made. This condition in the work is necessary, whether the knife is of disk or tubular form, to provide the relatively rigid and abrupt shoulder 30 which is desirable for the purpose of insuring uniformity and accuracy in the folding operation, as well as of avoiding the waste caused by the usual much greater folding allowance. However, the circular cut made by the tubular knife 24 minimizes the width of the skiving cut to the greatest possible extent.

40 The edge gage 18 is mounted opposite and adjacent to the inner end of the feed roll 10, rather than in overlapping relation thereto, in order that there will be no gap between them in which the edge of the work can become jammed. The gage is provided with a throat 144 (Fig. 5) which confines the edge of the work more and more as it is guided into the bite between the presser foot 22 and feed roll, where a shoulder 146 on the gage positions the edge of the work flush with the outer edge of the rim 14. This shoulder rises from a point, as high above the rim 14 as the work is thick, in an arcuate direction, as at 148, which is concentric with the pivot 20 about which the presser foot yields. Accordingly, there is no gap between the edge gage and presser foot in spite of such slight movement of the presser foot as may be caused by variations in the thickness of the work. Extending forwardly from the edge gage, and flush with the periphery of the rim 14, is a projection or table 150 upon which the margin of the work may flatly rest as it is drawn into the throat 144 of the gage.

50 60 70 75 The presser foot 22 is yieldingly urged toward

the feed roll 10 by a spring 152 (Fig. 4) which is seated within a recess in the right hand end of the edge gage. The upper end of this spring is engaged by a shoulder on a thumb screw 154 which is threaded in the right-hand end of the presser foot 22. A locknut 156, threaded on the screw 154, is arranged to hold it in adjusted position. A screw 158 passing through a clearance-hole in the presser foot and threaded into the edge gage 18 is arranged adjustably to limit the movement of the presser foot toward the feed roll, when there is no work in the machine. Provision for adjustment of the edge gage and presser foot transversely of the axis of the feed roll 10 is made by a slotted connection of the edge gage at 160 with a plate 162 to which the edge gage is secured by a screw 164.

The mounting of the plate 162 is substantially the same as in many patented machines of this type, the plate being adjustable at its lower end along a guide rib 166 which in turn is vertically and angularly adjustable upon another plate 168; this plate being hinged at 170 to a portion of the bearing 66. The guide rib and plate 162 are secured in adjusted position on the plate 168 by a screw 171 and a thumb nut 172 threaded on the screw. A knurled clamping nut 173 threaded upon a stud 174, the base of which is pivoted to the bearing 66, holds the plate 168 in its operative position. By unscrewing the nut 173 it may be freed from the plate 168, whereby the presser foot and edge gage may be swung away from the feed roll in order to provide access to the knife.

The skiving chips are discharged into the interior of the tubular knife 24 and are expelled therefrom as will now be described. Supported inside the knife and independently thereof is a waste tube 174 which extends through the rear end of the sleeve 32 into the knife and terminates adjacent to the cutting edge of the knife. This tube is somewhat smaller than the opening in the knife but is flared at 175 near its forward end so as to fit closely within the knife. In order to facilitate the movement of chips into the waste tube its end slopes upwardly away from the cutting edge of the knife, and is also beveled on the inside. Furthermore, the axis of the waste tube is offset slightly from that of the knife so that the above-mentioned flaring of the waste tube occurs only above its axis where it is not likely to be engaged by the skiving chips.

The chips are expelled from the waste tube by a blast of air directed into it through a tube or nozzle 176 which is carried by a cover 178 which forms a closure for that portion of the opening of the knife 24 not already covered by the presser foot and edge gage.

In order to provide access to the knife 24, the cover is mounted to swing away from the edge of the knife upon the lower part of the bearing 74, and may be clamped in either an inoperative position or its operative position by a clamp screw 180. An angular bracket 182 (Fig. 2) is arranged to hold the cover against the bearing 74 and is secured to the rear side of the frame 70 by screws 184.

The waste tube 174 is carried by a bracket 186, the latter being fixed on a rod 188 which is mounted for axial adjustment in a slide 190 so that the end of the tube 174 can be positioned in the desired relation to the knife-edge. A hose or pipe 192 (Fig. 7) is connected to the bracket 186 and is adapted to carry chips, which are blown out of the waste tube 174 into a suitable waste container.

The slide 190 (Figs. 2 and 3) serves as a base for a motor 194 which carries on the lower end of its shaft an abrasive wheel 196 for sharpening the knife 24. To enable the abrasive wheel to be brought into engagement with the knife, and in such a relation thereto as to provide the desired bevel upon the knife, the slide 190 is movable axially of the knife under the control of a knob 198, and also transversely of the knife under the control of another knob 200. The slide 190 is mounted for movement axially of the knife upon a slideway member 202, and is thus moved by a screw 204 threaded into the slideway member and carrying the knob 198 on its forward end. Between a pair of spaced collars 205, 206 fixed on the screw 204 there extends an arm 208 which projects forwardly from the slide 190. The slideway member 202 has a shank 210 which is seated upon the upper end of the standard 40, and is adapted to be clamped thereto by a screw 212 which passes through a slot in the shank and is threaded into the standard. Adjustment of the shank 210 to vary the position of the abrasive wheel 196 laterally of the knife, is effected by turning the knob 200 which is carried by a screw 214 threaded in the shank and mounted to rotate freely within a bracket 216 fixed to the standard 40.

The use and operation of the machine will now be briefly summarized. A work-piece to be skived is placed upon the feed roll 10 with its leading end underneath the feed disc 26, and with its edge slightly overlapping the rim 14 and the edge of the table 150 adjacent to the rim. As the work is fed into the bite between the presser foot 22 and the feed roll the edge of the work is positioned flush with the outer edge of the rim 14. Furthermore, the presser foot 22 causes the work to be bent into conformity to the sectional shape of the feed roll whereby an abrupt bend is imparted to the work close to its edge, as described above with reference to Fig. 6. Immediately upon leaving the presser foot the work is presented to the skiving knife 24 in the above-described bent condition. There is then produced at the edge of the work a very thin and short feather 28, which, when it straightens after passing behind the knife, projects abruptly from the shoulder 30 extending from the base of the feather across the flesh side of the work.

If, because of variations in the thickness or texture of the stock, its feeding movement is retarded, the movement of the feed disc 26 will be slowed down with the work. This action is permitted by the yielding drive provided by the spring 110. Before the feeding action of the disc can build up to the point where jamming of the work between the feed roll and presser foot could occur, slippage will occur between the clutch elements 96, 98.

As each chip leaves the work it passes into the central opening in the knife and thence into the tube 174 so that the rotation of the knife is ineffectual to cause the chips to be matted or held within the knife by the effect of centrifugal force. The constant blast of air emitted from the nozzle 176 expels the chips, once they are freed from the work, out of the rear end of the tube 174 and into the pipe 192 which delivers them into a waste container.

Having described my invention what I claim as new and desire to protect by Letters Patent of the United States is:

1. In a skiving machine, the combination with a skiving knife of a feed roll having at one end

a narrow rim and a portion contiguous thereto which are angularly disposed to each other to form a ridge over which the margin of the work is abruptly bent, an edge gage for positioning the edge of the work flush with the exposed end of said rim, and a presser foot constructed and arranged to hold the work at and at each side of said ridge against said roll thereby to form an abrupt bend in the work adjacent to its edge at the point of operation of said knife.

2. In a skiving machine, with a skiving knife and a feed disc, the combination of a feed roll having a central flared portion, a hub at one side of said flared portion cooperating with said feed disc to feed the work, and a rim at the other side of said flared portion, said flared portion being wider than said rim, and a presser foot constructed and arranged to hold the work against both said flared portion and said rim at each side of their junction.

3. In a skiving machine, with a skiving knife and a feed disc, the combination of a feed roll having a narrow rim at one end, said roll also having a frusto-conical surface extending from said rim with progressively diminishing diameter toward the midportion of the roll and a hub contiguous to the smaller base of said frusto-conical surface arranged to cooperate with said feed disc to feed the work, and a presser foot constructed and arranged to hold the work against said frusto-conical surface and rim immediately in front of said knife.

4. In a skiving machine, with a skiving knife and a feed disc, the combination of a feed roll having a narrow rim at one side thereof, said roll also having a frusto-conical portion extending from said rim with diminishing diameter toward the other side of said roll, said frusto-conical portion being wider than said rim, and a hub contiguous to the smaller base of said frusto-conical portion arranged to cooperate with said feed disc to feed the work, and a presser foot constructed and arranged to hold the work against said rim and frusto-conical portion immediately in front of said knife.

5. In a skiving machine, with a skiving knife and a feed disc, the combination of a feed roll having a narrow rim at one end thereof contiguous to a frusto-conical portion extending with diminishing diameter toward the other end thereof, said roll also having a hub arranged to cooperate with said feed disc to feed the work, a presser foot shaped and arranged to hold the work against said surface and said rim at their junction and at each side thereof, and a gage for positioning the work with its edge flush with the outer edge of said rim.

6. In a skiving machine, with a skiving knife and a feed disc, the combination of a feed roll having at one side a hub cooperating with said disc to feed the work and at the other side a narrow rim the width of which is approximately equal to the thickness of the work to be skived, an edge gage having a shoulder in juxtaposition to said rim, said gage also having a projection extending forwardly from said shoulder flush with said rim, and a presser foot arranged to hold the work against both said rim and the portion of said feed roll contiguous to said rim.

7. In a skiving machine, with a skiving knife and a feed disc, the combination of a feed roll arranged to cooperate with said feed disc to feed a work piece toward said knife, said roll having a narrow rim at one end thereof, said rim and the portion of said roll contiguous thereto being angu-

larly disposed to each other to form a ridge over which the margin of the work is bent, an edge gage having a shoulder facing and disposed in alignment with the exposed end of said rim, and a presser foot constructed and arranged to hold the work against said rim and the portion of said roll contiguous to said rim whereby an abrupt bend is imparted to the work over said ridge at the point of operation of said knife.

10. 8. In a skiving machine, with a skiving knife and a feed disc, the combination of a feed roll having a central flared portion, a rim at one side of said flared portion the width of which is approximately equal to the thickness of the work to be skived, and a presser foot having a work engaging face of inverted V-shape complementary in form to that of said rim and flared portion, said presser foot and roll being arranged to form an abrupt bend in the work adjacent to its edge at the point of operation of said knife, and an edge gage for positioning the edge of the work flush with the exposed end of said rim.

9. In a skiving machine, in combination, a knife, a rotating feed roll, a rotary feed disc mounted for movement toward and away from said feed roll, a spring arranged to urge said feed disc toward said feed roll, one end of said spring being connected with said feed disc, and means for driving the other end of said spring in rotation.

10. 10. In a skiving machine, in combination, a knife, a rotating feed roll, a rotary feed disc, means for driving said feed disc comprising a frictional clutch constructed and arranged to slip in response to a predetermined resistance to turning of said disc, and a spring for urging said feed disc toward said feed roll, one end of said spring being operatively connected with said clutch and the other end being connected with said feed disc whereby said feed disc is yieldingly driven in rotation.

11. In a skiving machine, in combination, a knife, a rotating feed roll, a rotary feed disc having a stem mounted to rotate and slide axially thereof, means for driving said feed disc comprising a rotating member which freely receives said stem, a collar mounted upon said stem for adjustment toward and away from said member, and a spring the ends of which are connected to said collar and member whereby said disc is both urged toward said feed roll and is yieldingly driven in rotation.

12. In a skiving machine in combination, a rotary tubular knife having a cutting edge formed upon one end thereof, means for forming an abrupt bend in the margin of a work piece and for progressively presenting the bent margin of the work piece to said knife, said means comprising a feed roll and a presser foot, said roll having a narrow rim and a portion contiguous thereto which are angularly disposed to each other to form a ridge over which the margin of the work is abruptly bent, said presser foot being constructed and arranged to hold the work against said rim and said contiguous portion of the roll and at each side of their junction, a rotatable disk cooperating with said roll to feed the work toward said knife, and means for yieldingly driving said disk in rotation.

13. In a skiving machine in combination, a feed roll having a narrow rim and a hub at the opposite ends thereof, said rim and hub being connected by a frusto-conical section extending with diminishing diameter from said rim to said hub, a presser foot shaped and arranged to hold the

margin of a work piece against said rim and said frusto-conical section at their junction and at each side thereof, a tubular skiving knife having a cutting edge formed upon one end thereof immediately adjacent to said presser foot, a rotatable disk cooperating with said hub to feed the work piece toward said knife, and means for yieldingly driving said disk in rotation.

MILTON H. ROSKE. 10
